Patented Aug. 3, 1926.

UNITED STATES PATENT OFFICE.

PAUL F. VOKAL, OF HARTFORD, CONNECTICUT, ASSIGNOR TO PRATT & WHITNEY COMPANY, OF NEW YORK, N. Y., A CORPORATION OF NEW JERSEY.

GRINDING-WHEEL DRESSING ATTACHMENT.

Application filed July 24, 1924. Serial No. 727,829.

My invention relates to dressing attachments for truing thread grinding wheels and to methods of dressing thread grinding wheels.

5 One object of my invention is to provide a dressing attachment that shall true a plurality of grinding ridges on a thread grinding wheel in a new and an improved manner.

10 Another object of my invention is to provide a method of dressing a thread grinding wheel that shall true a number of grinding ridges on the wheel in an efficient manner.

In grinding many threaded articles, such 15 for example as taps, it has been customary heretofore to grind the threads by means of a grinding wheel having a single grinding ridge. When a grinding wheel having a single grinding ridge is used for grinding a 20 tap, it is necessary to rotate the tap as many times during the grinding operation as the number of turns of thread. Thus, in a thread of small pitch, the grinding operation extends for a considerable length of 25 time. In a grinding machine having a wheel dressed in accordance with my invention a single grinding wheel is provided with a plurality of grinding ridges. The time of 30 the grinding operation, when using a wheel having a number of ridges, is cut down in accordance with the number of grinding ridges on the wheel. It should also be noted 35 that one grinding wheel will grind a number of threads having different pitches. For example, if the grinding ridges are set a quarter of an inch apart, it is possible to 40 grind any thread having an even multiple of four threads per inch.

In a grinding attachment constructed in 45 accordance with my invention, it is possible to true a number of grinding ridges on a grinding wheel in an efficient manner so as to cut threads having an exact angle and a uniform lead.

45 In the accompanying drawings:

Figure 1 is a plan view of a thread grinding machine provided with my truing attachment.

50 Figs. 2 and 3 are respectively plan and side elevational views of a dressing bar for cutting fillets between the grinding ridges of the wheel.

55 Fig. 4 is an enlarged plan view of my dressing attachment.

Fig. 5 is a side elevational view of the 55 attachment shown in Fig. 4.

Fig. 6 is an end view of the attachment shown in Fig. 4.

Figs. 7 and 8 are respectively side elevational and end views of the dressing bar for 60 truing the sides of the grinding ridges.

Fig. 9 is an enlarged view showing a grinding wheel in engagement with a tap.

Fig. 10 is a diagrammatic view showing the angular relation of the wheel axis to the 65 blank axis.

Referring to the drawings and particularly to Fig. 1, a headstock 1 and a tailstock 2 are shown mounted on a carriage 3. The work piece, which in the machine under consideration is a tap, is secured between the centers of the head and tailstock. A grinding wheel 4 is mounted on a shaft 5. The shaft 5 is carried in any suitable manner upon a wheel slide 6. Adjacent to the grinding wheel 4 and carried by the slide 6 is a dressing slide 7. The dressing slide 7 carries a dressing plate 8 which will be described more fully hereinafter. A hand wheel 9 is provided for effecting movement 70 not only of the wheel slide 6 but also of the dressing slide 7 when a dressing operation is being performed. The hand wheel 9 moves the wheel slide 6 twice the distance 75 through which the dressing slide 7 is moved in order to maintain the grinding wheel 4 in correct relation with respect to the work. The plate 8 is mounted on the slide 7 in a plane parallel to the axis of the blank being 80 operated on. The shaft 5 of the wheel 4 is 85 set at an angle to the blank axis in accordance with the helix angle of the thread on the blank. The gearing connection between the two slides is fully described and 90 illustrated in the companion application of 95 Carl Schramm and Paul F. Vokal, Serial No. 717,794, filed June 4, 1924.

The carriage 3, which supports the headstock 1 and the tailstock 2, is moved longitudinally in timed relation to the rotation 100 of the headstock spindle. A full description of the gearing connection for operating the carriage and headstock spindle is set forth in the above mentioned application of Schramm et al. and accordingly a detailed 10 description in this application is deemed unnecessary. It may be noted, however, that a hand wheel 10 is provided for adjusting

the position of the carriage 3 on the main frame of the machine and a hand wheel 11 is provided for adjusting the position of the wheel slide 6.

8 The grinding wheel 4 is provided with six grinding ridges numbered 12 to 17, inclusive. Each of the grinding ridges is shaped to grind the thread of a tap. The ridges have the same shape and are evenly spaced 10 apart so that each grinding ridge engages a certain part of the thread on the tap when in operation. Referring to Fig. 9 of the drawings, it will be noted one turn of the thread is disposed between each pair of grinding ridges. Accordingly, it would take only two complete turns of the tap to grind the complete thread. If the grinding wheel were only provided with one grinding ridge, it is apparent the tap would have to 20 be rotated as many times as the turns of the thread in order to completely grind such thread.

23 The grinding wheel under discussion is not restricted to one pitch but may be used to grind threads of different pitch. Thus, if the grinding ridges are disposed exactly a quarter of an inch apart, it is apparent such grinding wheel will grind a tap having 30 four threads, eight threads, twelve threads, or any multiple of four threads per inch. Accordingly, it is apparent only a very limited number of grinding wheels are required for grinding all the taps of usual size.

25 The plate 8, which is secured to the dressing slide 7, is provided with two sets of guiding grooves 18 and 19. The sets of grooves 18 and 19 form an angle with each other which exactly corresponds with the angle of the thread to be ground. The 40 grooves in each set of grooves are separated from each other a distance which corresponds to the pitch of the thread which is formed on the work piece. If the grinding ridges on the wheel are separated a quarter of an inch, as is necessary in grinding a pitch having four or eight threads per inch, the grooves in the set 18 and the set 19 must be separated from each other a distance such 50 that the distance between such grooves on a line parallel to the blank axis is a quarter of an inch.

55 If a grinding wheel is provided for grinding taps having three threads, six threads or a multiple of three threads per inch, the grinding ridges on the grinding wheel will be located a third of an inch apart and the grooves in the sets 18 and 19 would be separated from each other so that the distance 60 between the grooves on a line parallel to the axis of the blank would be one third of an inch. The sets of grooves 18 and 19 serve to guide a dressing bar 21 for truing the side surfaces of the ridges 12 to 17, inclusive, on the grinding wheel 4. The grooves in the set 18 serve to true one side of the ridges

and the grooves in the set 19 serve to true the other side of the ridges. A groove 22 is formed in the plate 8 parallel to the axis of the grinding wheel. Such groove 22 serves to guide the dressing bar 21 for truing the 70 peripheral edge of each of the ridges 12 to 17, inclusive.

75 The dressing bar 21, as illustrated in Figs. 7 and 8, of the drawings, is provided with two cutting points 23 and 24. The point 24 is used for dressing the side surfaces of the ridges 12 to 17, inclusive, and the cutting point 23 is used to dress the peripheral edges of the grinding ridges. The dressing bar 21 is provided with two projecting ridges 80 25 and 26 which are so shaped as to fit the grooves in the sets of grooves 18 and 19 and the groove 22. During the dressing of the peripheral edges of the grinding ridges by the cutting point 23, the ridge 25 or the ridge 85 26 is operated in the groove 22. When truing one side surface of each ridge by the cutting point 24, the ridge 26 is operated in the sets of grooves 18 and when truing the 90 opposite sides of the ridges by the cutting point 24, the ridge 25 is operated in the grooves of the set 19. Two positions of the dressing bar 21 are indicated in Fig. 4 of the drawings. In Fig. 10 of the drawings, the angular relation of the blank axis $a-a$ to the wheel axis $b-b$ is illustrated. The angle between such axes, as heretofore set forth, corresponds to the helix angle of the blank thread. The dressing bar 21 trues 100 the grinding ridges of the wheel 4 on a line parallel to the axis of the blank. In such manner the wheel is trued to cut correct threads while being placed to insure against cutting away the side of the thread being ground. 105

A dressing bar 28, which is illustrated in Figs. 2 and 3 of the drawings, is provided for cutting fillets 30 in the grinding wheel between the various grinding ridges. Such fillets 30 are provided to permit the dressing of the side surfaces of the ridges by the cutting point 24 to a sufficient depth. The dressing tool 28 is provided with a cutting point 31 mounted on an end portion 32 which is so shaped as not to engage the side surfaces of the ridges when the fillets are being formed in the wheel. 110 115

120 In dressing a grinding wheel in accordance with my invention, the fillets 30 are first formed in the wheel between the grinding edges by means of the dressing bar 28. If so desired, the bar 28 may be rested upon the dressing plate 8 during the forming of such fillets. The dressing bar 21 is next operated 125 in the groove 22 for dressing the peripheral edges of the grinding ridges by means of the cutting point 23. The cutting point may be advanced toward the grinding wheel by means of the hand wheel 9. Finally, the side 130 surfaces of the grinding ridges 12 to 17, in-

clusive, are dressed by means of the cutting point 24, the dressing bar 21 being guided by the sets of grooves 18 and 19 as before described.

Although I have illustrated my invention by a grinding wheel composed of but six grinding ridges, it is to be understood that the grinding wheel may be provided with any desired number of such ridges. Moreover, the spacing of the ridges and the shape thereof may be varied in accordance with the threads being ground.

Modifications in the attachment and in the arrangement and location of parts may be made within the spirit and scope of my invention and such modifications are intended to be covered by the appended claims.

What I claim is:

1. In a dressing attachment for the wheel of a thread grinding machine, the combination comprising a plate having two sets of guide grooves formed therein, the sets of said grooves making an angle with each other corresponding to the angle of the thread being ground, and a dressing bar guided by said grooves for dressing the sides of a plurality of grinding ridges on the grinding wheel.

2. In a dressing attachment for the wheel of a thread grinding machine, the combination comprising a plate having two sets of guide grooves formed therein, the sets of said grooves making an angle with each other corresponding to the angle of the thread being ground, and a dressing bar guided by said grooves for dressing the sides of a plurality of grinding ridges on the grinding wheel, said plate having a groove parallel to the axis of the grinding wheel for guiding said bar to dress the periphery of the ridges on the wheel.

3. In a dressing attachment for the wheel of a thread grinding machine, the combination comprising a plate having two sets of guide grooves formed therein, the sets of said grooves making an angle with each other corresponding to the angle of the thread being ground, a dressing bar guided by said grooves for dressing the sides of a plurality of grinding ridges on the grinding wheel, and a second dressing bar for forming an enlarged fillet between the ridges formed on the wheel, said plate being set at an angle to the axis of the wheel during the dressing operation.

4. In a dressing attachment for the wheel of a thread grinding machine, the combination comprising a plate having two sets of guide grooves formed therein, the sets of said grooves making an angle with each other corresponding to the angle of the thread being ground, a dressing bar guided by said grooves for dressing the sides of

a plurality of grinding ridges on the grinding wheel, said plate having a groove parallel to the axis of the grinding wheel for guiding said bar to dress the periphery of the wheel, and a second dressing bar for forming an enlarged fillet between the ridges formed on the wheel.

5. In a dressing attachment for a thread grinding wheel having a plurality of annular grinding ridges, the combination comprising a guide plate having two sets of guide grooves formed therein, the sets of grooves making an angle with each other corresponding to the angle of the thread being ground and the grooves of each set being spaced apart a distance corresponding to the pitch of the thread being ground, and a dressing bar guided by one set of said grooves for dressing one side of each of said ridges and guided by the opposite set of said grooves for dressing the opposite side of each ridge.

6. In a dressing attachment for a thread grinding wheel having a plurality of annular grinding ridges, the combination comprising a guide plate having two sets of guide grooves formed therein, the sets of grooves making an angle with each other corresponding to the angle of the thread being ground and the grooves of each set being spaced apart a distance corresponding to the pitch of the thread being ground, a dressing bar guided by one set of said grooves for dressing one side of each of said ridges and guided by the opposite set of said grooves for dressing the opposite side of each ridge, said plate having a groove parallel to the axis of the grinding wheel for guiding said bar to dress the periphery of the ridges.

7. In a dressing attachment for a thread grinding wheel having a plurality of annular grinding ridges, the combination comprising a guide plate having two sets of guide grooves formed therein, the sets of grooves making an angle with each other corresponding to the angle of the thread being ground and the grooves of each set being spaced apart a distance corresponding to the pitch of the thread being ground, a dressing bar guided by one set of said grooves for dressing one side of each of said ridges and guided by the opposite set of said grooves for dressing the opposite side of each ridge, said plate having a groove parallel to the axis of the grinding wheel for guiding said bar to dress the periphery of the grooves, and means comprising a slide for moving the plate perpendicularly with respect to the axis of the wheel.

In testimony whereof, I hereto affix my signature.

PAUL F. VOKAL.
